UNITED STATES PATENT OFFICE.

HOLLINGSWORTH B. BARRET, OF SHREVEPORT, LOUISIANA.

AEROPLANE.

1,095,782.

Specification of Letters Patent.

Patented May 5, 1914.

Application filed January 9, 1913. Serial No. 741,070.

To all whom it may concern:

Be it known that I, HOLLINGSWORTH B. BARRET, a citizen of the United States, residing at Shreveport, in the parish of Caddo and State of Louisiana, have invented certain new and useful Improvements in Aeroplanes; and I do hereby declare the following to be a full, clear, and exact description of the invention, such as will enable others skilled in the art to which it appertains to make and use the same.

My invention relates to aeroplanes, and it consists in the constructions, combinations and arrangements herein described and claimed.

An object of my invention is to provide an aeroplane having an improved sustaining plane constructed to provide a maximum sustaining power and stability.

20 A further object of my invention is to provide an aeroplane having simple and efficient means for automatically maintaining stability.

A further object of my invention is to 25 provide an improved aeroplane having automatic stabilizing means adapted to act constantly and with certainty under all practical conditions.

A further object of my invention is to 30 provide an improved aeroplane having emergency means for maintaining a headway upon failure of the propeller drive.

A further object of my invention is to 35 provide an aeroplane having improved guiding means under control of the aviator.

In the accompanying drawings forming a part of this application, and in which similar reference symbols indicate corresponding parts in the several views:—Figure 1 is a 40 plan view, illustrating one embodiment of my invention; Fig. 2 is an elevation of the construction shown in Fig. 1; Fig. 3 is a detail side view of the sustaining plane and means for adjustably supporting one of the 45 guide planes along the lateral edge thereof; Fig. 4 is a detail elevation of the gyroscope, partly broken away, to show the automatical clutch drive from the motor; Fig. 5 is a section on the line 5—5 of Fig. 4; Fig. 6 is a 50 detail view of the drive connection between the gyroscope and auxiliary propeller, parts being broken away for clearness; Fig. 7 is a section on the line 7—7 of Fig. 6; and Fig. 55 8 is an enlarged fragmentary section of the means for locking the gyroscope in its several adjusted positions.

Referring to the drawings, 1 indicates the longitudinal members and 2 the transverse members of a main frame, to which is strongly secured a sustaining plane formed with a downwardly-concave body portion 3 and terminating in a plane front portion 4 and an upwardly-turned rear portion 5; the frame being mounted on ground-wheels 6 and 7 adapted to incline the front portion 4 of the plane slightly upward when starting on level ground. In this improved construction of plane, the air forced rearwardly under the upwardly-inclined front portion 4 thereof impinges strongly on the downwardly-concave body portion 3 and is gradually deflected thereby downwardly across the lower surface of the rear portion 5 of the frame; the final upwardly curved surface of said rear portion 5 acting effectively to 75 automatically prevent rearward diving of the plane upon stoppage of the propeller from any cause. Spaced stabilizing planes 8 are rigidly secured to the sustaining plane and extend vertically from the upper and lower faces thereof. This provides an improved and highly advantageous construction having a maximum sustaining power and stability.

I have shown seats 9 for an aviator and 80 passenger supported on the sustaining plane in position to be effectively shielded by the concave body portion 3 of said plane; suitable levers or other usual devices being provided in convenient position for controlling 85 the rudders and other parts in the well known manner.

A main propeller 10 is journaled in a bearing 11 supported for universal movement on the main frame; the shaft 12 of 90 said propeller being connected by a universal joint 13 to a drive shaft 14 driven in any suitable manner, as by bevel gears 15, by an air cooled motor 16 preferably of the 95 rotary reciprocating type. This provides a 100 simple and efficient construction by which the main propeller 10 can be readily shifted for varying its action to meet all practical conditions.

A bracket 17 is pivoted at 18 on the main 105 frame, and carries a gyroscope 19 and a drive motor 20 therefor; said gyroscope being shown provided with a closed casing for minimizing friction. The upper end of the gyroscope spindle 21 is journaled in a block 110 22 slidably mounted in a guide 23 curved concentrically with the pivot 18; a nut 24

being threaded on said block for clampingly engaging the upper face of said guide to firmly lock said block 22 in its several adjusted positions. I have shown an arm 25 projecting from the nut 24, which can be connected to a link extending in convenient position for actuating by the aviator for locking and unlocking said nut. This provides an improved construction by which 10 the plane of rotation of the gyroscope can be readily shifted to insure the best effect under all practical conditions, such as starting on inclined ground, etc.

A shaft 26 is driven by intermeshing 15 gears 27 carried in a hollow cap 28 supported on the block 22; said shaft 26 extending slidably and rotatably in a hollow shaft 29 and being provided with a keyway 30 for receiving a tooth or key formed 20 on one member of a detachable clutch 31, 32. The hollow shaft 29 is connected by a universal joint 33 with the spindle of an auxiliary propeller 34, whereby said propeller can be driven by the gyroscope upon shifting 25 of the clutch members 31 and 32 into engagement by the aviator. This provides means by which the auxiliary propeller can be driven to maintain a headway upon failure or stoppage of the main propeller 10 from any cause, and as the gyroscope 19 will 30 run for a considerable length of time even upon accidental stoppage of its motor 20, the auxiliary propeller 34 could ordinarily be driven for a sufficient length of time to 35 permit a safe landing. The gyroscope 19 is driven by any well known form of friction clutch 35 to permit the continued free forward rotation of said gyroscope upon stoppage of its motor.

40 Guiding planes 36 are pivoted at 37 to the main frame and provided with blocks 38 and 39 slidably mounted in curved guides 40 and 41 mounted on the main frame concentric with said pivot 37; suitable connections, such as wires 42 and 43 being led to

a convenient position for actuating of said guiding planes by the aviator.

I have illustrated and described preferred and satisfactory constructions, but changes could be made within the spirit and scope of 50 my invention.

I claim:—

1. The combination with an aeroplane of a frame pivotally mounted thereon; a curved guide bar mounted concentrically 55 with the pivot of said frame; a gyroscope mounted on said pivoted frame, and having a shaft engaging with said curved guide bar; a device carried by the gyroscope shaft for securing the same in adjusted positions 60 on said curved bar; a propeller; a driving shaft having a universal joint connecting the propeller with the gyroscope shaft and adapted to be adjusted therewith; and a motor mounted on the pivoted frame for 65 driving the gyroscope and the propeller, substantially as described.

2. The combination with an aeroplane of a frame pivotally mounted thereon; a curved guide bar mounted concentrically 70 with the pivot of said frame; a gyroscope mounted on said pivoted frame, and having a shaft engaging with said curved guide bar; a device carried by the gyroscope shaft for securing the same in adjusted positions on 75 said curved bar; a propeller shaft; a propeller mounted on said propeller shaft; a shaft comprising slidably-engaging sections having a universal joint connection with the propeller shaft; intermeshing pinions 80 connecting said gyroscope shaft and said sectional shaft; and a motor mounted on the pivoted frame for driving the gyroscope and the propeller, substantially as described.

In testimony whereof, I affix my signature, in presence of two witnesses.

HOLLINGSWORTH B. BARRET.
